UNITED STATES PATENT OFFICE.

CARL HARLMER CARLSON, OF BURLINGTON, IOWA.

LOCK.

No. 834,709.

Specification of Letters Patent.

Patented Oct. 30, 1906.

Application filed January 31, 1906. Serial No. 298,780.

To all whom it may concern:

Be it known that I, CARL HARLMER CARLSON, a citizen of the United States, residing at Burlington, in the county of Des Moines and State of Iowa, have invented certain new and useful Improvements in Locks, of which the following is a specification.

My invention relates to improvements in locks, and refers to a particular form of tumbler-lock.

The main object of the invention is the provision of a lock which will be adapted to a variety of uses and which will require a key of novel and unusual form, thereby rendering the lock proof against unlawful interference.

Other objects of the invention are to provide a lock which will have simple mechanism and be durable in construction and which will be very efficient and positive in its operation.

With these and other objects in view my invention consists of a lock comprising a casing, a locking-bolt in the casing, a series of locking-tumblers engaging the locking-bolt, recesses of various sizes formed in the tumblers, and a key having projections to engage the corresponding recesses in the tumblers.

My invention further consists of a lock embodying certain other novel features of construction, combination, and arrangement of parts, substantially as disclosed herein.

Figure 1 is a front elevation of my improved lock in operative position. Fig. 2 is a vertical sectional view of the lock with the locking-bolt, tumblers, and key shown in elevation. Fig. 3 is a perspective view of one of the tumblers. Fig. 4 is a similar view of the key.

Referring to the drawings, the numeral 1 designates the casing or shell of the lock, provided with the flattened end portions 2 for securing the lock in position. Longitudinal parallel passages or channels 3 are formed in the casing, and intersecting the base of these passages is the transverse passage 4, which extends through both side walls of the casing. Adapted to slide in the transverse or horizontal passage is the locking-bolt 5, having the shouldered portion 6 adapted to abut against the walls of the casing to limit the movement of the locking-bolt and prevent removal thereof from the casing. At one end the locking-bolt is plain, as at 7, to engage the seat 8, formed in the bolt receiver or keeper 9, and at the other end it is formed

with a handle or grasping portion 10. In the side of the bolt opposite the shouldered portion it is formed with seats or recesses 11 in line with the parallel channels in the casing. 63

Slidably mounted within the parallel channels are the tumblers 12, which are the same length as said channels, and the ends of these tumblers are adapted to engage the recesses in the locking-bolt. Shallow recesses 13 are 65 formed in the upper faces of the tumblers, and the recesses in the tumblers are of different length or size. The partition-walls between the tumblers are cut away or recessed, as at 14, and the wall of the casing is 70 provided with a keyway or opening 15 to correspond to the recesses of the tumblers when said tumblers are in engagement with the locking-bolt. In this particular lock the first tumbler is formed with a comparatively 75 long recess and the other tumblers with recesses of lesser length. A flat key is provided, having a handle portion 16, and on the under side it is provided with a flat face 17, adapted to rest on the locking-bolt when 80 the key is inserted in the lock. On the upper side the key is formed with the lugs or projections 18 of different lengths and adapted to engage the corresponding recesses in the tumblers. 85

After the key has been inserted in the lock it is simply necessary to raise the key, which action lifts the tumblers and disengages them from the locking-bolt, and the locking-bolt can then be moved to release it from the 90 keeper.

It will be readily seen that the key cannot be withdrawn from the lock until the locking-bolt is in the closed or locked position. Thus an extra safeguard is provided, which 95 insures of the lock being left in the closed or locked position.

Many different locks may be made on this plan without departing from the spirit of the invention, such as changing the number of 100 the tumbler-bars, the size of the recess therein, the width of the channel-walls, and numerous other minor details of construction.

From this description, taken in connection with the drawings, it will be obvious that I 105 have accomplished the objects herein set forth and have provided a durable and reliable lock which will be adaptable to a great many uses.

I claim—

1. The combination with a casing having 110 tumblers mounted parallel therein, of a locking-bolt slidably mounted at right angles to

the tumblers and formed with recesses in one edge, the tumblers adapted to engage said recesses when the bolt is projected, recesses formed in the upper faces of the tumblers beginning on a line with the edge of the bolt when the tumblers are seated therein, a key adapted to enter the casing resting flush on the edge of the bolt and the recesses in the tumblers, and means for limiting the movement of the bolt.

2. The combination with a casing having tumblers mounted parallel therein, of a locking-bolt slidably mounted at right angles to the tumblers formed with recesses in one

edge for the reception of the tumblers and 15 having a shouldered extension on its upper edge to engage the walls of the casing and limit the movement thereof, recesses formed in the upper faces of the tumblers, and a key adapted to enter the casing resting flush on 20 the edge of the bolt and the recesses in the tumblers.

In testimony whereof I affix my signature in presence of two witnesses.

CARL HARLMER CARLSON.
